(57) **CLAIM**

The ornamental design for a bottle, as shown and described.

DESCRIPTION

1. Bottle
- 1.1 : Front
- 1.2 : Back
- 1.3 : Right
- 1.4 : Left
- 1.5 : Top
- 1.6 : Bottom
- 1.7 : Cross-sectional
- 1.8 : Cross-sectional
- 1.9 : Cross-sectional
- 1.10 : Cross-sectional

Figure 1.7 is an enlarged cross-sectional view of cut edge of the bottle when the bottle is cut horizontally across the middle of the bottle, and seen from top view; figure 1.8 is an enlarged cross-sectional view of the bottle when the bottle is cut horizontally across the upper part of the bottle, and seen from top view; figure 1.9 is an enlarged cross-sectional view of cut edge of the bottle when the bottle is cut horizontally across the bottom part of the bottle, and seen from top view; figure 1.10 is a longitudinal cross-sectional view of cut edge of the bottle when the bottle is cut vertically down the middle of the width of the bottle at right view, and seen from the front side.

(Continued)

In the reproductions, the broken lines are for the purpose of illustrating portions of the bottle that form no part of the claimed design.

1 Claim, 10 Drawing Sheets
